UNITED STATES PATENT OFFICE

163,760

ELECTRIC POWER TOOL UNIT

Frank Lustig, Chicago, Ill., assignor to Excel Auto
Radiator Company, Chicago, Ill., a corporation
of Delaware

Application June 12, 1950, Serial No. 10,475

Term of patent 14 years

(Cl. D54—14)

To all whom it may concern:

Be it known that I, Frank Lustig, a citizen of the United States, residing at Chicago, State of Illinois, have invented a new, original, and ornamental Design for an Electric Power Tool Unit, of which the following is a specification, reference being had to the accompanying drawing, forming a part hereof.

Fig. 1 is an elevational view of an electric power tool unit, showing my new design;

Fig. 2 is an elevational view of the power tool turned 90° on its axis from the position illustrated in Fig. 1;

Fig. 3 is a rear end view thereof, and

Fig. 4 is a front end view thereof.

I claim:

The ornamental design for an electric power tool unit, as shown.

FRANK LUSTIG.
